UNITED STATES PATENT OFFICE.

WINCENT NELDNER, OF MILWAUKEE, WISCONSIN.

DESIGN FOR A KNIFE.

54,669.

Specification for Design.

Patented Mar. 9, 1920.

Application filed September 11, 1919. Serial No. 323,229. Term of patent 7 years.

To all whom it may concern:

Be it known that I, WINCENT NELDNER, a citizen of Poland, residing at Milwaukee, in the county of Milwaukee and State of Wisconsin, have invented a new, original, and ornamental Design for a Knife, of which the following is a specification, reference being had to the accompanying drawing, forming part thereof.

The figure is a view in perspective of a knife, showing my new design.

I claim:

The ornamental design for a knife, as shown.

WINCENT NELDNER.
